CARL H. BISSELL, OF SYRACUSE, NEW YORK, ASSIGNOR TO CROUSE-HINDS COMPANY,
OF SYRACUSE, NEW YORK, A CORPORATION OF NEW YORK.

MOTOR-STARTING SWITCH.

1,336,064.

Specification of Letters Patent.

Patented Apr. 6, 1920.

Application filed February 7, 1916. Serial No. 76,678.

To all whom it may concern:

Be it known that I, CARL H. BISSELL, a citizen of the United States, and a resident of Syracuse, in the county of Onondaga and 5 State of New York, have invented a certain new and useful Motor-Starting Switch, of which the following is a specification.

This invention relates to motor starting switches and has for its object a particularly simple and efficient arrangement of 10 means for controlling the movement of the switch and for housing the switch; and the invention consists in the combinations and constructions hereinafter set forth and 15 claimed.

In describing this invention, reference is had to the accompanying drawings, in which like characters designate corresponding parts in all the views.

20 Figure 1 is a side elevation, partly broken away, of this switch and its housing.

Fig. 2 is a longitudinal sectional view thereof.

Fig. 3 is a plan view, partly broken away.

25 Fig. 4 is a detail view of one end of the switch arm or yoke, and contiguous parts.

This invention comprises generally, a box open at one side, a cover for the open side of the box, a detachable casing mounted on the 30 side of the box, a switch located in the casing including two sets of contacts and a movable switch member shiftable from neutral or "off" position to carry terminals thereof into engagement with the first set of contacts and in the opposite direction to carry 35 terminals thereof into engagement with the second set of contacts, means for operating the switch member including a rock shaft extending transversely through the side of the box and through said casing, and means 40 within the casing for controlling the movement of the movable switch member.

1 designates the box which is here shown as cast in one piece and as having its upper 45 side open at 2 and as having means, as a threaded nipple 3, for connection with an electric conduit.

4 is the cover for the open side 2, which cover is hinged at 5 at one end of the box, 50 and is provided with a latch 6 at the other end thereof, coacting with a suitable shoulder 7 arranged between lugs 8 on the box 1, one of these lugs being formed with a perforation 9 through which a locking means 55 can be passed as the shackle of a padlock,

said perforation 9 being so arranged that the shackle will come into the path of the pivotal movement of the latch 6 and prevent unlatching thereof. The cover 4 is formed with a projecting dome-shaped portion 4^a in 60 which moves the movable switch member and its blades.

10 is the casing on one side of the box, this casing being detachably secured to the side of the box, as by screws 11. 65

12 designates the base of the switch; 13, one set of terminals, and 14 the second set of terminals thereof.

15 designates the movable switch member as a whole, said switch member including a 70 yoke or bar 16 carrying two sets of terminals or blades 17 and 18 arranged to engage respectively with the contacts 13 and 14. The yoke or bar 16 is formed with down-turned ends 19, one of which is formed with 75 a conical seat for receiving the conical end 20 of a pin or screw 21 extending through the side of the box 1 opposite that on which the casing 10 is located. The other down-turned end 19 is formed with a slot 22 opening through the end of said arm, for receiving one end of the rock shaft 23 by means of which the movable switch member is operated. A key 24, is passed transversely through the slotted end of the bar 16 and 80 through the end of the shaft 23. Upon the removing of the key 24 the corresponding end of the member 16 can be raised so that the opposite arm 19 can be readily detached 85 from the conical pointed pin 20. 90

The rock shaft 23 is journaled in a suitable bearing 25 in one side of the casing, and extends transversely through said side and through the casing 10 and the side wall thereof, and is provided with a handle lever 95 26 at its outer end, which is secured thereto in any suitable manner as by the key 26^a.

The rock shaft 23 is normally positioned so that the movable switch member is in neutral or "off" position, and a spring 27 100 is associated therewith which is arranged so that when the switch member is shifted in one direction to carry the terminals 17 into engagement with the contacts 13, the spring is tensioned to shift the movable switch 105 member in the reverse direction upon the release of the handle, to carry the terminals 18 into engagement with the contacts 14.

The means for controlling the operation of the switch member, operates to normally 110

prevent movement of switch member from neutral position to carry the terminals 18 into engagement with the contacts 14 but to permit movement of the switch member from neutral position to carry the terminals 17 into engagement with the contacts 13, and to also permit movement of the switch member to carry the terminals 18 into engagement with the contacts 14 after said member has been shifted to carry the terminals 17 into engagement with the contacts 13. This controlling means comprises a rock arm 28 mounted on the shaft 23 within the casing 10 and having a laterally extending pin 29 at one end, and a detent 30 mounted upon a shaft or arbor 31 and having a hook shaped end arranged in the path of the pin 29 when the switch member is in neutral position to normally prevent movement of the rock shaft 23, rock arm 28 and switch member 15 in one direction, that is, in such direction as to carry the terminals 18 from neutral position into engagement with the contacts 14. Said means also includes detent shifting means as a rock arm 32 mounted on shaft 31 and arranged in the path of the pin 29 and movable thereby so that the pin 29 will ratchet past said rock arm 28, when the rock shaft 23 is operated to carry the terminals 17 into engagement with the contacts 13. The rock arm 32 has a shoulder 33 arranged to engage the detent 30, so that when the rock arm 28 is moved in the opposite direction after it has ratcheted past the rock arm 32, the rock arm 32 by reason of said shoulder 33 will shift the detent out of the path of the pin 29 so that the movable switch member is shifted by the spring 27 to carry the terminals or blades 17 out of engagement with the contacts 13, and past neutral position to carry the terminals or blades 18 into engagement with the contacts 14. Suitable returning springs 34, 35 are connected to the detent 30 and the shifting arm 32 respectively. The springs 34, 35 are connected at corresponding ends to a pin or anchor common to both springs and the spring 35 is connected at its upper end to the hub of the arm 32 mounted on the shaft 31 and the spring 34 is similarly connected to the hub of the arm 30 also mounted on said shaft. The handle lever 26 is provided with a bifurcated extension 27^a which is arranged to come opposite a slot 36 in a lug 37 on the casing 10, when the switch member is in neutral position, this slotted lug being for the purpose of receiving the locking member as the shackle 38 of a padlock which shackle also extends between the bifurcations of the handle lever. A similar lug 39 is provided in such position that the switch member can be locked in its "on" position. In operation, the handle normally stands in neutral position, and upon the movement

thereof to the right, Fig. 1, the rock arm 28 moves upwardly carrying the pin 29 above the detent shifting arm 32 by moving the arm 32 upwardly about its axis 31 and tensioning the spring 35 until the end of the 70 arm 28 slips off from the end of the arm 32 owing to the fact that the arc in which the end of the arm 32 moves is in the opposite direction from the arc in which the pin 29 on the arm 28 moves. The spring 35 then 75 contracts and causes said arm 32 to snap into a position below the pin or shoulder 29. This movement of the handle tensions the spring 27 on the rock shaft 23 and also carries the terminals 17 into engagement with the contacts 13. Upon release of the handle, the spring 27 moves the rock shaft 23 and the arm 15 in the opposite direction and the pin 29 now bearing on the upper side of the shifting arm 32 pushes said arm downwardly and to the left, and the shifting arm 32 owing to the fact that its shoulder 33 bears upon the upper edge of the detent 30 and forces the detent 30 out of the path of the pin 29 so that the switch arm can be 90 moved by the spring 27 to carry the terminals 18 into engagement with the contacts 14, the pin passing below and along a ratcheting surface 40 on the detent.

When it is desired to move the switch arm to neutral position it is operated by hand and the pin 29 ratchets along the surface 40 until the pin 29 ratchets into the position shown in Fig. 1. During the movement of the switch handle in a retrograde direction 100 to open the switch and break the circuit, the pin 29 passes along the ratcheting surface 40 and cams the detent 30 to the left, Fig. 1 and tensions the spring 34 until said pin clears the point of the hook of the detent whereupon the spring retracts and again pulls the detent into its starting position as shown in Fig. 1.

This controlling mechanism forms the subject-matter of my patent, #1,116,552, 110 November 10, 1914, in which the controlling mechanism is covered in its broad aspect. This invention includes the same general features of the invention of said patent, but is directed to a different and in some respects more simple and compact arrangement than the mechanism of said patent.

This invention is particularly advantageous in that it provides a particularly simple and efficient arrangement of the motor 120 starting switch and its controlling mechanism.

What I claim is:

1. A motor starting switch comprising two sets of contacts, a movable switch member, means for operating the movable member including a shaft, a rock arm connected to said shaft to be actuated thereby, and means for controlling the movement of the shaft including a detent normally coacting 130

- with the rock arm to prevent movement thereof in one direction, when the switch member is in neutral or "off" position, and a detent shifting arm extending into the path 5 of movement of the rock arm in the opposite direction from neutral or "off" position, the shifting arm being arranged to permit the rock arm to ratchet past the same and having a shoulder for engaging the detent and 10 forcing the same out of the path of the rock arm when the rock shaft is moved to carry said rock arm in the first direction, after the rock arm has ratcheted past the shifting arm, substantially as and for the purpose 15 specified.
2. A motor starting switch comprising two sets of contacts, a movable switch member, means for operating the movable member of the switch including a shaft and a 20 rock arm actuated by said shaft, and means for controlling the movement of the switch member including a detent normally coacting with the rock arm to prevent movement thereof in one direction from neutral or 25 "off" position, a detent shifting arm extending into the path of movement of the rock arm in the opposite direction from neutral or "off" position, the shifting arm being arranged to permit the rock arm to 30 ratchet past the same and having a shoulder for engaging the detent and forcing the same out of the path of the rock arm when the rock shaft is moved to carry said rock arm in the first direction after the rock arm 35 has ratcheted past the shifting arm, the

shifting arm and the detent being mounted on a common pivot, and springs resisting pivotal movement thereof by the first rock arm, substantially as and for the purpose 40 described.

3. A motor starting switch comprising a box open at one side, a cover for the open side of the box, a switch located in the box and including two sets of contacts and a switch member movable about an axis located within the box, and a shaft extending through the side of the box in axial alignment with the switch member, the switch member being mounted on the shaft, the switch member being movable in one direction from neutral position to carry terminals thereof into engagement with one set of the contacts and in the opposite direction to carry terminals thereof into engagement with another set of contacts, a handle 55 mounted on the shaft on the outside of the box, means carried by the side of the box adjacent the shaft for controlling the movement of the shaft and the switch member to carry terminals thereof first into engagement with the one set of contacts before the shaft can move to carry terminals of the switch into engagement with the other set of contacts, substantially as and for the 60 purpose specified.

In testimony whereof I have hereunto signed my name, at Syracuse, in the county of Onondaga and State of New York, this 13th day of December, 1915.

CARL H. BISSELL.
